HEDDLE FRAME

George R. Plott, near Concord, N. C.

Application July 12, 1944, Serial No. 544,476

8 Claims. (Cl. 138—92)

This invention relates to a heddle frame and more especially to a heddle frame having heddle bars for supporting the heddles therein, with means for releasably and detachably mounting the heddle bars in the heddle frame so that they can be quickly inserted in place and quickly removed from the frame together with the heddles carried thereby.

It is an object of this invention to provide in a heddle frame, means for detachably mounting the heddle bars in a fixed position so that they can be easily removed from the frame.

It is another object of this invention to provide in a heddle frame having upper and lower bars and side bars connecting the same together to provide means whereby the top and bottom heddle bars can be detachably mounted on the vertically disposed bars at each end of the frame so that they can be quickly mounted in position and quickly removed from the frame.

It is a further object of this invention to provide means for detachably supporting the heddle bars in a heddle frame at each end thereof with supplemental means for also supporting the heddle bars at a plurality of points intermediate their ends.

Some of the objects of the invention having been stated, other objects will appear as the description proceeds, when taken in connection with the accompanying drawing, in which:

Figure 1 is an elevation of a heddle frame equipped with my invention with the central portion thereof broken away;

Figure 2 is a vertical sectional view through the lower left-hand portion of Figure 1;

Figure 3 is an elevation looking from along the line 3—3 in Figure 1;

Figure 4 is a vertical sectional view taken along the line 4—4 in Figure 1;

Figure 5 is a vertical sectional view taken along the line 5—5 in Figure 1;

Figure 6 is a horizontal sectional view taken along the line 6—6 in Figure 1;

Figure 7 is an elevation of a portion of the lower left-hand corner of Figure 1, and showing the securing cuff in elevated position.

Referring more specifically to the drawing, the numerals 10 and 11 indicate the upper and lower frame members of a heddle frame, and these are joined together by suitable bars or rods 12 and 13. The bars 10 and 11 are held in spaced relation on bars 12 and 13 by means of the ends of the rods or bars 12 and 13 being threaded and having suitable nuts 14 disposed above and below the horizontal bars for holding them in spaced

relation. The upper bar 10 has a pair of looped members 16 by means of which suitable straps or other supporting means are secured thereto for supporting the heddle frame. Similar loops 15 or members similar to 16 also project downwardly from the bar 11, but since these are conventional, they are not shown.

Secured in the bars 10 and 11 and projecting from proximate surfaces thereof are looped members 17 having hooks 18 pivotally secured at one end thereto and the other end being hooked as at 19 and being adapted to hook over heddle supporting bars 20. These heddle supporting bars are adapted to be detachably supported at their 20 ends on the vertically disposed bars 12 and 13 by means of notches 21 being cut in the sides of these rods 12 and 13, and these notches are restricted at their outer ends or beveled inwardly so that the heddle bars 20 have to be slid endwise into these notches so that they cannot be pulled directly outwardly laterally of the notches. The heddle bars 20 have in each end thereof a perforation or hole 23, and there are slidably mounted on the rods 12 and 13 cuff members 25 which have outwardly projecting ears 26 and 27 and also have a slot 28 therein. These cuff members are adapted to be slid outwardly, as for example, from the position shown in Figure 7 to the position shown in Figure 1, and suitable bolts 31 are passed through perforations 29 in the projections or ears 26 and 27 which also penetrate the holes 23 in the ends of the bars 20 to thus not only securely affix the ends of the heddle bars to the cuff members, but due to the fact that 35 the cuff members have a relatively close sliding fit with the rods 12 and 13 they prevent any tendency for the bars 20 to have lateral movement while the cuffs 25 are in the position shown in Figure 1.

40 The heddle bars 20 are adapted to support heddles 30 in a conventional manner thereon and only a few of these heddles 30 are shown as they are supposed to extend all the way across the frame for the entire length of the heddle bars 20 from post 12 to 13.

When the nuts on bolts 31 are loosened, the cuffs 25 can be slid along their respective rods and in the drawing, the cuff is shown spaced from its associated rod, but when the nut on bolt 31 is driven home to bring the ears 26 and 27 against the opposed sides of the heddle bar 20, it will bring the interior surface of the cuff 25 into clamping engagement with its associated rod.

55 In the drawing and specification, there has been

set forth a preferred embodiment of the invention, and although specific terms are employed, they are used in a generic and descriptive sense only, and not for purposes of limitation, the scope of the invention being defined in the claims.

I claim:

1. In a heddle frame having horizontally disposed frame members and vertically disposed end bars disposed between the ends of the horizontal frame members, a pair of heddle bars, means for removably anchoring the ends of the heddle bars to the vertically disposed end bars comprising the vertically disposed frame members having cavities therein into which the heddle bars are adapted to fit and cuff members surrounding the vertically disposed end bars and slidably fitting over the ends of the heddle bars, and means penetrating the slideable members and heddle bars for releasably locking the slideable cuff members to the heddle bars and to the vertically disposed end bars.

2. In a heddle frame for looms having horizontal frame members provided with end bars forming a part of the frame, said end bars having cavities in one side thereof, a pair of heddle bars whose end portions are adapted to fit in said cavities and slideable members mounted on the end bars and adapted to fit over the ends of the heddle bars, and means for securing the slideable members to the ends of the heddle bars.

3. In a heddle frame for looms having upper and lower horizontal frame portions, a pair of end bars having notches in one side thereof and joining the upper and lower frame portion of the frame together, a pair of heddle bars for supporting heddles, means for releasably anchoring the heddle bars to the end bars comprising members slidably mounted on the end bars and each having a slot therein adapted to fit over a heddle bar and having a pair of lugs extending therefrom, the lugs and the ends of the heddle bars having coinciding holes therethrough through which bolts are adapted to be passed to secure the members to the end bars and the heddle bars.

4. In a heddle frame comprising upper and lower frame members and end bars secured to the frame members and spanning the distance therebetween, a pair of heddle bars, the end bars having cavities therein into which the heddle bars are adapted to fit and each end bar having slidably mounted thereon adjacent to the end of each heddle bar a cuff member having a slot therein adapted to fit over the heddle bar and having a pair of ears projecting therefrom, the ears and the end of the heddle bar having coinciding holes therethrough through which a bolt is adapted to be passed for clamping the slideable cuff member around the end bar and for firmly securing the heddle bar in the cavity in the end rod.

5. In a heddle frame having horizontally disposed frame members and vertically disposed end bars disposed between the ends of the horizontal frame members, a pair of heddle bars, means for removably anchoring the ends of the heddle bars to the vertically disposed frame members comprising the vertically disposed frame members having cavities therein into which the heddle bars are adapted to fit and cuff members surrounding the vertically disposed frame members

and slidably fitting over the ends of the heddle bars, and means penetrating the slideable cuff members and heddle bars for releasably locking the slideable members to the heddle bars and to the vertically disposed frame members, each cavity in the end bars being of lesser width at its outer edge than the width of a heddle bar, but increasing in width as it extends into the end bar whereby the heddle bar must be inserted endwise into the cavity and cannot be withdrawn laterally therefrom.

6. In a heddle frame for looms having horizontal frame members provided with end bars forming a part of the frame, said end bars having cavities in one side thereof, a pair of heddle bars whose end portions are adapted to fit in said cavities and slideable members mounted on the end bars and adapted to fit over the ends of the heddle bars, and means for securing the slideable members to the ends of the heddle bars, each cavity in the end bars being of lesser width at its outer edge than the width of a heddle bar, but increasing in width as it extends into the end bar whereby the heddle bar must be inserted endwise into the cavity and cannot be withdrawn laterally therefrom.

7. In a heddle frame for looms having upper and lower horizontal frame portions, a pair of end bars having notches in one side thereof and joining the upper and lower frame portions of the frame together, a pair of heddle bars for supporting heddles, means for releasably anchoring the heddle bars to the end bars comprising members slidably mounted on the end bars and each having a slot therein adapted to fit over a heddle bar and having a pair of lugs extending therefrom, the lugs and the ends of the heddle bars having coinciding holes therethrough through which bolts are adapted to be passed to secure the members to the end bars and the heddle bars, each notch in the end bars being of lesser width at its outer edge than the width of a heddle bar, but increasing in width as it extends into the end bar whereby the heddle bar must be inserted endwise into the notch and cannot be withdrawn laterally therefrom.

8. In a heddle frame comprising upper and lower frame members and end bars secured to the frame members and spanning the distance therebetween, a pair of heddle bars, the end bars having cavities therein into which the heddle bars are adapted to fit and each end bar having slidably mounted thereon adjacent to the end of each heddle bar a cuff member having a slot therein adapted to fit over the heddle bar and having a pair of ears projecting therefrom, the ears and the end of the heddle bar having coinciding holes therethrough through which a bolt is adapted to be passed for clamping the slideable cuff member around the end bar and for firmly securing the heddle bar in the notch in the end bar, each notch in the end bars being of lesser width at its outer edge than the width of a heddle bar, but increasing in width as it extends into the end bar whereby the heddle bar must be inserted endwise into the notch and cannot be withdrawn laterally therefrom.

GEORGE R. PLOTT.
